FAN-TYPE AIR HEATER

Carl J. Fay, Guy E. Shawk, and John W. Harrison, Mansfield, Ohio, assignors to Westinghouse Electric & Manufacturing Company, East Pittsburgh, Pa., a corporation of Pennsylvania

Application February 26, 1941, Serial No. 380,650

2 Claims. (Cl. 219—39)

Our invention relates to air heaters and, more particularly, to fan-type convection heaters.

It is an object of our invention to provide an inexpensive convection type heater which may be assembled as a unit and then mounted in an enclosing shell or casing.

It is a further object of our invention to provide a rugged inexpensive fan-type convection heater having a fan motor and heating element mounted coaxially therewith with a single supporting bracket structure for mounting said fan motor and heating element as a unit to a supporting exterior casing or shell.

It is a still further object of our invention to provide a method of assembling a fan type convection heater having a fan motor, a baffle therefor, and a heating element by utilizing a single or unitary supporting bracket structure for coaxially mounting the fan motor baffle and heating element within a supporting casing or shell.

Other objects of our invention will either be pointed out specifically in the course of the following description of a device embodying our invention or will be apparent from such description.

In the accompanying drawings:

Figure 1 is a longitudinal sectional view of a device embodying our invention;

Fig. 2 is a rear view of the device shown in Fig. 1 with the exterior guard members removed; and,

Fig. 3 is a schematic wiring diagram of the device embodying our invention.

Referring to the accompanying drawings, there is illustrated a fan-type convection air heater 10 which includes an outer casing or shell 12, a motor 14 and attached fan 15, a cylindrical baffle 16 positioned around the motor 14, a heating element 18 mounted coaxially with the motor 14, baffle 16 and casing 12, and a plurality of mounting brackets 20 attached at one end to the baffle 16 for rigidly mounting the fan motor 14, baffle 16 and heating element 18 as a unit to the casing or shell 12.

The exterior enclosing casing 12 comprises, in this instance, a hollow cylindrical shell-like structure open at both ends. Suitable screens or guard structures 22 are removably attached to the casing at each end thereof, as a protective medium for preventing an operator's hand, for example, from being injured by the fan or heating element. A suitable handle 23 is attached to the upper portion of the casing 12 to provide means for moving the heater 10. In 55

addition, a substantially Y-shape bracket structure 24 is attached to the sides of the casing 12 and provide means for supporting the casing from, for example, either a platform or a wall. The Y-shaped supporting structure 24 also permits the heater 10 to be rotated or moved to any desired position, such as, for example, about the bolts 25, as a horizontal axis and about the bolt 27, as a vertical axis.

10 The fan 15 is removably attached to the rotating shaft of the fan motor 14 which is adapted to drive such fan to draw air through the heater. The fan 15 and fan motor 14, being no part of our present invention, may be of any desired conventional design.

A hollow cylindrical baffle 16 having a diameter slightly greater than that of the motor 14, is positioned about such motor to prevent direct radiation of heat from the heating element 18 coming in contact with the motor frame. Suitable supporting brackets 20 are attached to the motor and to the inner surface of the baffle 16 to provide supporting means for the motor 14.

An air deflector 26 is attached to the end of the baffle 16 furthest away from the fan 15. Such deflector 26 extends outwardly from the baffle towards the fan and heating element so as to direct the flow of air passing through the heater away from the baffle and through such element. The deflector 26 by being attached to the end of the baffle 16 tends to strengthen such baffle, and, accordingly, permits somewhat lighter metal to be used in the construction thereof.

Mounting or supporting brackets 20 comprising, in this instance, substantially elongated strip type members, extend radially outwardly from the baffle 16 to provide means for supporting such baffle 16 and motor 14. The mounting brackets 20 are rigidly attached to the baffle 16 and air deflector 26 and are spaced substantially 120° apart from each other. The brackets 20 have rigidly attached to a point substantially intermediate the ends thereof a supporting member 21 which is adapted to extend toward the fan 15 and substantially parallel to the axis of the baffle 16 and motor 14. These supporting members 21 being rigidly attached to the brackets 20 are adapted to receive the heating element 18 which is wound about or positioned upon such members. The supporting members 21 are positioned upon the brackets at such a point as to enable the heating element 18 to be disposed thereupon with its axis substantially coaxial with that of the motor and baffle. It is to be understood that any desired type or shape of sup-

porting member may be used in lieu of those described providing they support the heating element substantially coaxially with the motor 14 and baffle 16, and provided that they be rigidly attached to the brackets 20.

The heating element 18 comprises, in this instance, a helically wound metallic encased heating unit 28 which has disk-like radiating fins 30 attached to the metallic casing thereof. The heating element comprises, in this instance, substantially 1½ turns of the heating unit. However, such element may be formed of any desired material of any suitable length or shape depending upon the desired heat output. The disk-like heater radiating fins 30 are of such character as to rest upon the supporting members 21 and support the heating element 18 therefrom. A suitable bracket 32 is positioned upon and drawn toward the supporting members by means of, say, a bolt 34. This bracket 32, in cooperation with the supporting member 21, thus provides means for rigidly supporting the heating element 18 from the supporting brackets 20 substantially coaxially with respect to the motor 14 and baffle 16.

The motor 14 is connected to a suitable power supply 41 by means of, in this instance, either of two switches 38 and 40. The main switch 38 is adapted to energize both the motor 14 and heating element 18. In contrast, switch 40 merely energizes the motor 14, permitting the fan 15 and motor 14 to operate without the heating element being energized.

As a protective feature, thermostat 42 is attached to the outside of the baffle 16 so as to be in the air stream. This thermostat is connected in series with the heating element 18 (see schematic wiring diagram—Fig. 3) and functions as a protective device therefor. The thermostat is normally cooled by the air flow and should the flow of air cease for any reason, while the heating element is energized, such thermostat will disconnect the heating element from the power supply 41.

When constructing the heater 10 embodying our invention the fan motor 14 is rigidly attached to the inner portion of the baffle 16 which has the air deflector 26 attached thereto, by means of the suitable foot-like base or supporting structure 29. The motor 14 is positioned within the baffle 16 so that the fan 15 will be positioned beyond the end of the baffle 16 opposite to the end which supports the air deflector. The supporting members 20 are also rigidly attached to the baffle 16 at the same end. The heating element 18 is then positioned upon the supporting members 21 so as to form a unitary structure embodying the fan motor 14, baffle 16, air deflector 26, supporting bracket 20, and heating element

18. This unitary structure may then be readily and easily positioned within any suitable casing or shell-like structure 12 and rigidly attached thereto, say, by means of suitable bolts 36.

5 It is, therefore, obvious that we have provided a fan-type convection heater in which the heating element is rigidly attached to the fan motor and supporting bracket so as to form a unitary structure. This type of structure thus facilitates 10 the manufacture thereof and provides means for readily disassembling, inspecting and repairing of the heating element, for example.

Various modifications may be made in the device embodying our invention without departing 15 from the spirit and scope thereof, and we desire, therefore, that only such limitations shall be placed thereon as are imposed by the prior art and the appended claims.

We claim as our invention:

20 1. In a convection type heater having an outer casing, a cylindrical baffle, a motor centrally located within the baffle for driving a fan and a heating element located intermediate the baffle and casing, the combination of a plurality of radially extending brackets rigidly attached at one end thereof to the baffle, a plurality of supporting members attached to said brackets radially intermediate the ends thereof and extending 25 in the direction of the baffle, means independent of said brackets for rigidly attaching the heating element to said members, and means for fastening the other ends of said supporting brackets to the casing for independently attaching said motor, fan, baffle and heating element 30 as a unit to the casing.

35 2. In a convection type heater having an outer casing, an inner hollow baffle, a fan, a fan motor attached thereto and mounted within said baffle substantially coaxially therewith, and a heating element positioned about the baffle intermediate said baffle and outer casing, the combination of 40 a plurality of radially extending mounting brackets attached at one end thereof to the baffle for mounting said baffle and fan motor as a unit coaxially within the outer casing, inwardly extending supporting members each having one end attached to the respective brackets radially intermediate the ends thereof for engaging one side of the heating element independent of the outer casing, a plurality of clamping members 45 engaging the opposite side of the heating element, said supporting and clamping members being substantially radially aligned in pairs, and means for rigidly securing the paired members 50 together.
